UNITED STATES PATENT OFFICE.

WALTER WILLIAM FONDREN, OF HOUSTON, TEXAS.

PACKER FOR WELLS.

1,382,770.

Specification of Letters Patent. Patented June 28, 1921.

Application filed January 10, 1921. Serial No. 436,293.

To all whom it may concern:

Be it known that I, WALTER WILLIAM FONDREN, a citizen of the United States, residing at Houston, in the county of Harris and 5 State of Texas, have invented certain new and useful Improvements in Packers for Wells, of which the following is a specification.

This invention relates to new and useful 10 improvements in a packer for wells.

The object of the invention is to provide a device of the character described, which is particularly adapted for use in oil wells, and whereby a water tight joint may be formed 15 between an outer and an inner pipe.

The packer is interposed between oil and water strata to prevent the mingling of water with the oil, and is also used to force the oil to enter the pipe through the screen 20 or strainer, and to prevent the same from passing up between the pipe and the well casing. The device herein described may be used anywhere it is desirable to form a joint between an inner and outer pipe.

25 With the above and other objects in view, the invention has particular relation to certain novel features of construction, arrangement of parts and use, an example of which is given in this specification and illustrated 30 in the accompanying drawings, wherein:—

Figure 1 is a sectional view of the packer in position to be set, and

Fig. 2 is a sectional view, showing the packer set and in position to case off water 35 and prevent the passage of fluid between the outer casing and the inner pipe.

Referring now more particularly to the drawings, wherein like numerals of reference designate similar parts in each of the figures, the numeral 1 refers to a casing, which 40 is set in a well bore. When the well bore has been completed, as is well known to those familiar with the art of oil well drilling, a strainer or screen is set in the oil bearing strata at the bottom of the bore. This 45 screen has not been shown in the drawings, but may be attached to the lower end of the pipe section 2. The upper end of this section is outwardly threaded as at 3, and surrounding the lower end thereof, is a collar 4, which is fixed thereon by means of a set screw 5. Threaded over the upper end of the section 2 is the sleeve 6, and interposed 50 between said sleeve and collar is a packer ring 7, preferably formed of lead, or some other soft metal. When the sleeve 6 is

screwed down onto the section 2, it will cause the packer ring 7 to bulge outwardly against the casing all around the section 2, forming a water tight joint. For the purpose of applying the packer ring, I have provided the upper and lower collars 8 and 9, which are connected by means of the nipple 10, said collars being screwed onto the respective ends of said nipple by means of right hand 60 threads, and the lower end 11 of the collar 9 has external left hand threads, adapted to be screwed in the corresponding threads 12 in the upper end of the section 2. A pair of oppositely disposed dogs 13, 13 are provided 65 which are interposed between the collars 8 and 9 and whose respective ends have the fingers 14 and 15, which have the required radial movement in radially extending slots, cut in the adjacent ends of the respective collars 8 and 9. These dogs are seated on the 70 respective springs 16, 16, interposed between them and the nipple 10. The device is first assembled into the position shown in Fig. 1, and then attached to a pipe by means of 75 which it is let down into the well casing to the desired point. The pipe is then rotated in the usual direction, causing the collar 9 to unscrew from the section 2. The pipe is then lifted a short distance, elevating the collars 80 8 and 9 until the dogs 13 clear the upper end of the elevator 6. The dogs are then forced outwardly by the spring 16, and project beyond the collar 8, as shown in Fig. 2. A rotation of the pipe will cause said dogs to 85 aline with the opposing notches 17, 17, provided in the upper end of the sleeve 6, and said dogs will drop into said notches and a further rotation of the pipe will operate to rotate the sleeve 6, and it will be screwed 90 downwardly onto the section 2, forcing the packer ring 7 out against the casing, as shown in Fig. 2, thereby forming a water tight joint in the manner shown, and for the 95 purposes hereinabove explained. When the 100 packer has been set, the device may be then withdrawn from the well, if it is so desired.

What I claim is:—

1. A device of the character described, including a pipe section, a packer surrounding 105 the same, a sleeve threaded onto said section and adapted to abut against said packer to expand the same, a rotatable member fitted within the sleeve and capable of being connected with and disconnected from said 110 pipe section, radially movable dogs carried by said member, yieldable members operat-

ing against said dogs, and tending to force them outwardly, the upper end of the sleeve being provided with notches into which said dogs project when brought into alinement therewith, thus forming a connection between the rotatable member and the sleeve through which the sleeve may be rotated against said packer to expand the same.

2. A device of the character described for 10 setting a well packer in a well, including a sleeve adapted to be screwed on the pipe carrying said packer, a rotatable member fitted within the sleeve, radially movable dogs carried by said member, yieldable members 15 operating against said dogs and tending to force them outwardly, the upper end of the sleeve being provided with notches into which said dogs project when brought into alinement therewith, thus forming a 20 connection between the rotatable member

and the sleeve, through which the sleeve may be rotated.

3. A packer setting mechanism, including a sleeve, a rotatable member within the sleeve, radially movable dogs carried by the 25 said member, yieldable members operating against the dogs and tending to force them outwardly, interengaging means carried by the upper end of the sleeve with which the dogs are arranged to engage when brought 30 into alinement therewith, to prevent the relative rotation of said member and the sleeve.

In testimony whereof I have signed my name to this specification in the presence of two subscribing witnesses.

WALTER WILLIAM FONDREN.
